(57) **CLAIM**

The ornamental design for a window component extrusion, as shown and described.

DESCRIPTION

FIG. 1 is a perspective view of a window component extrusion according to the present invention, the broken edge indicating that the length of the extrusion continues.

FIG. 2 is a left side view of the window component extrusion of FIG. 1.

FIG. 3 is a right side view of the window component extrusion of FIG. 1.

FIG. 4 is a front elevation view of the window component extrusion of FIG. 1.

FIG. 5 is a rear elevation view of the window component extrusion of FIG. 1.

FIG. 6 is a top view of the window component extrusion of FIG. 1; and,

FIG. 7 is a bottom view of the window component extrusion of FIG. 1.

The portions of the design shown in dashed lines do not form a part of the claimed invention.
